PIN-UP LAMP

Marion Axelrod, East Gloucester, Mass.

Application June 17, 1953, Serial No. 25,541

Term of patent 7 years

(Cl. D48—4)

To all whom it may concern:

Be it known that I, Marion Axelrod, a citizen of the United States of America, residing at East Gloucester, county of Essex, and Commonwealth of Massachusetts, have invented a new, original, and ornamental Design for a Pin-Up Lamp, of which the following is a specification, reference being had to the accompanying drawing, forming a part thereof.

Fig. 1 is a top plan view of a pin-up lamp embodying my new design.

Fig. 2 is a left side elevation thereof.

Fig. 3 is a front elevation thereof.

Fig. 4 is a right side elevation thereof.

Fig. 5 is a rear elevation thereof.

The dominant features of my design are shown in solid lines.

I claim:

The ornamental design for a pin-up lamp, substantially as shown and described.
